(57) **CLAIM**

I claim, the ornamental design for a glove for sports, as shown and described.

DESCRIPTION

FIG. 1 is a perspective view of a glove for sports showing my new design;

FIG. 2 is a perspective front view thereof;

FIG. 3 is a perspective rear view thereof;

FIG. 4 is a left side view thereof;

FIG. 5 is a right side view thereof;

FIG. 6 is a top view thereof; and,

FIG. 7 is a bottom view thereof.

The broken lines in FIGS. 1-7 represent portions of the glove for sports and form no part of the claimed design.

1 Claim, 7 Drawing Sheets
